(57) **CLAIM**

The ornamental design for a display screen with animated graphical user interface as shown and described.

DESCRIPTION

FIG. 1 is the first image in a sequence for a display screen with animated graphical user interface showing our new design;

FIG. 2 is the second image thereof;

FIG. 3 is the third image thereof; and,

FIG. 4 is the fourth image thereof.

The peripheral broken line shows a display screen and a boundary of the claimed design. The broken line forms no part of the claimed design. The broken lines depicting the alphanumeric characters form no part of the claimed design. The appearance of the graphical user interface sequentially transitions between the images shown in FIGS. 1-4. The process or period in which one image transitions to another forms no part of the claimed design.

1 Claim, 4 Drawing Sheets
